UNITED STATES PATENT OFFICE

HARVE R. STUART, OF WILKINSBURG, PENNSYLVANIA, ASSIGNOR TO
WESTINGHOUSE ELECTRIC & MANUFACTURING COMPANY, A COR-
PORATION OF PENNSYLVANIA.

VOLTAGE-REGULATOR.

No. 825,986.

Specification of Letters Patent.

Patented July 17, 1906.

Application filed April 14, 1904. Serial No. 203,226.

To all whom it may concern:

Be it known that I, HARVE R. STUART, a citizen of the United States, and a resident of Wilkinsburg, in the county of Allegheny and State of Pennsylvania, have invented a new and useful Improvement in Voltage-Regulators, of which the following is a specification.

My invention relates to apparatus for varying the voltage of alternating-current circuits; and it has for its object to provide a simple, compact, and commercially-efficient apparatus for raising and lowering alternating-current voltages that are so high or the attendant currents of which are so large that the regulators heretofore generally employed have been found inadequate or unsatisfactory for the service.

My invention is primarily intended and especially adapted for use in practicing the invention set forth in Patent No. 740,173, granted to the Westinghouse Electric & Manufacturing Company on an application filed jointly by John S. Peck and myself.

While the said patent sets forth all the essential elements of a regulator adapted for practical service conditions, my present invention embodies developments and improvements which have structural and functional characteristics of importance and value in commercial operations and at the same time includes the essential features of the said patent.

Figure 1 of the accompanying drawings is a diagrammatic view of a system of distribution in connection with which my invention is adapted to be employed. Fig. 2 is an end view of the regulator, a portion of the case being broken away. Fig. 3 is a sectional view on line III III of Fig. 4. Fig. 4 is a plan view of the regulator, the cover being removed. Fig. 5 is a detail sectional view of one of the gear-wheels of the apparatus and the driving-dogs therefor. Fig. 6 is a detail sectional view taken on line VI VI of Fig. 4. Fig. 7 is a longitudinal sectional view of a portion of the operating mechanism shown in Figs. 2 and 4. Fig. 8 is a sectional view taken on line VIII VIII of Fig. 7. Fig. 9 is a sectional view on line IX IX of Fig. 4 looking toward the left, and Fig. 10 is a similar view on line X X of Fig. 4 looking toward the right.

As set forth in the above-mentioned patent, a main transformer 1, comprising a primary winding 2, which is subdivided by 55 means of spaced leads 3, and a secondary winding 4, is supplied from distributing line conductors 5. In series with the primary winding 2 of the transformer 1 is the secondary winding 6 of a series transformer 7, 60 one terminal 8 of the primary winding 9 of which is connected to a point 10, which is between the windings 6 and 2, and the other terminal 11 of which is connected directly to contact-terminals 12 of switches 13 and 14. 65 The other contact-terminal 15 of the switch 13 is connected to contact-terminals 16 and 17 of switches 18 and 19, and contact-terminal 20 of the switch 14 is connected to contact-terminals 21 and 22 of switches 23 and 24, the other contact-terminal of the switches 18, 19, 23, and 24 being properly connected to the spaced leads 3. A preventive resistance 25 is connected between the contact-terminals 15 and 20 of the switches 13 and 14. 75

When the switches 14 and 24 are closed, the primary winding 9 of the series transformer 7 is short-circuited, and hence full-line voltage is impressed upon the primary winding 2 of the main transformer 1, and in 80 order to impress a different voltage upon the primary winding the operation consists in closing switch 19, opening switch 24, closing switch 13, and opening switch 14. These operations being completed, the primary circuit of the series transformer will be through the winding 9 to the terminal 11, through switch 13, switch 19, portion 26 of the primary winding 2, to the terminal 8 of the primary winding of the series transformer. The 85 next succession of operations consists in closing switch 23, opening switch 19, closing switch 14, and opening switch 13; whereby section 27 of the primary winding 2 of the main transformer 1 is introduced into the circuit of the primary winding 9 of the series transformer 7. The remaining operations of each of the steps are effected in a similar manner.

If it is desired to return from any voltage 100 to the last preceding voltage or if it is desired to reverse the voltage-changing steps, the operations must occur in a precise order. For instance, if it is desired to return from the

- above last-described positions of the switches to the next preceding positions the operations will be effected by closing switch 19, opening switch 23, closing switch 13, and opening switch 14. The apparatus here shown as embodying my invention comprises means for causing these switches to open and close in the proper order both when the voltage is to be raised and when it is to be lowered.
- 10 Journaled in one end of a case or frame 28 is a short shaft 29, to the outer end of which is secured a crank-arm 30 and to the inner end of which is secured a pinion 31, which has a laterally-projecting lug 31^a. Between the 15 pinion 31 and the case and loosely mounted upon the shaft 29 is a cam-wheel 32, having two laterally-projecting lugs 32^a in position to engage the pinion-lug 31^a and having a depression 33 in its periphery adapted to receive a roller 34, which is mounted upon a lever 35. One end of the lever 35 is pivoted to a lug 36, and to its other end is attached a spring 37, which serves to hold the roller 34 in engagement with the periphery of the cam 32. The 20 cam-wheel 32 and the coöperating devices above described are utilized in order to invariably stop rotation of the shaft 29 at the point which insures the proper coöperative relation of the switch-operating devices to be 25 hereinafter described. A pointer 30^a may also be provided to afford a visual indication of the proper position of rest for the operating mechanism. The lost-motion connection between the cam-wheel 32 and the pinion 31, 30 which is provided by the lugs 31^a and 32^a, corresponds to the lost motion of certain of the switch-operating devices, which takes place when the direction of motion is reversed.
- 35 40 Meshing with the pinion 31 is a gear-wheel 38, which is rigidly secured upon a shaft 39 by means of a pin 39^a, said shaft having bearings at 40 and 41. A quill 42, having cams 43 and 44, is loosely mounted upon the shaft 39, the cams having approximately the same shape, but being disposed on opposite sides and near opposite ends of the quill, as indicated in Figs. 4 and 7. By means of a dog 45 at one end of the quill 42, which is adapted 45 to engage with the one side or the other of a lug 46 on the gear-wheel 38, the cams 43 and 44 are actuated at proper intervals whether the voltage of the circuit is to be increased or decreased.
- 50 55 One end of the shaft 39 is keyed to a quill 47, having a gear-wheel 48 and having a feather connection with one end of a shaft 49. (See Fig. 7.) The opposite end of the shaft 49 is provided with threads 50, which engage 60 with a stationary nut 51, and at proper intervals throughout its length it is provided with cams 52, 53, 54, and 55, which have approximately the same form, but are disposed alternately upon opposite sides of the shaft.
- 65 Pivoted to stationary brackets 56 by means

of rods 57 are levers 58, which are severally provided at their front ends with rollers 59 to bear upon the peripheries of the corresponding cams 52 53, &c. The rear ends of the levers 58 are provided with screws 60, having lock-nuts 60^a, said screws constituting adjustable stops for the levers. Toggle-lever arms 61 are also pivotally supported at their front ends upon the rods 57 and at their rear ends are connected to toggle members 62, which in turn are pivoted at their other ends to switch-levers 63. Adjusting means for the toggle-levers are provided at the jointed ends of the levers 62, comprising screws 64 and lock-nuts 65.

70 The front ends of the switch-levers 63 are pivotally supported upon a shaft 66, and the other ends are connected, by means of links 67, to switch-rods 68. Disposed alternately on opposite sides of the shaft 66 and rigidly 75 secured thereto are cams 69, which are adapted to engage at the proper instants with the members 62, and thereby cause the toggle-joints to buckle. While the movement of the levers 58 is gradual, because dependent 80 upon the rotation of the cams 52 53, &c., the buckling of the toggle-joints is sudden, since there is no rigid connection between the levers 58 and the members 61, and consequently the switches are allowed to open 85 quickly. A gear-wheel 70, which meshes with the gear-wheel 48, is loosely mounted upon the shaft 66 and is provided on one face with two lugs 71, between which fits a dog 72, that is rigidly fastened to the shaft 66. 90 The opposite face of the gear-wheel 70 is provided with a lug 71^a, so located as to be engaged by a dog 72^a, that is rigidly fastened to the shaft 66. When the gear-wheel 70 is rotated, the lug 71^a engages the one side or the 95 other of the dog 72^a, according to the direction of rotation, and thereby effects rotation of the shaft 66. When the direction of rotation of the gear-wheel 70 is reversed, the lug 71^a has a path of movement of considerable 100 length before it engages the other side of the dog 72^a to effect rotation of the shaft 66 in the opposite direction.

105 The switches may be of any desired type of construction, those which I have shown comprising movable switch-arms 73, contact-terminals 73^a, attached to the ends thereof, and stationary terminals 74, adapted to be engaged by said movable terminals, all of 110 which are suitably mounted in reservoirs 75, 115 which may contain oil.

120 When the crank-arm 30 is rotated in a direction such as to cause a rise in voltage, the gear-wheel 38 is rotated by the pinion 31, and the lug 46 engages the dog 45, thereby causing the quills 42 and 47, the cams 43 and 44, and the shaft 49 to rotate in the same direction as the crank-arm. The gear-wheel 48 causes its corresponding gear-wheel 70 to rotate, so that the lug 71^a engages the dog 72^a, 125 130

and thus effects rotation of the shaft 66. If the shaft 49 be rotated sufficiently from the position shown in Fig. 4, the cam 53 will be brought into engagement with the roller 59 at one end of the corresponding lever 58 and will gradually effect closure of the switch 19, and the switch 24 will be opened after the switch 19 is fully closed by reason of the engagement of the proper cam 69 with the toggle-levers which operate the switch 24. After the switch 24 is opened the cam 44 will engage the roller 59 at one end of the corresponding lever 58 and cause the switch 13 to close, and switch 14 will be then opened by reason of the buckling of its corresponding toggle-joint by the engagement therewith of the corresponding cam 69. As the shaft 49 is rotated it is also given a longitudinal motion by reason of its threaded connection 20 with the stationary nut 51, and cams 52, 53, 54, and 55 will thus be caused to engage successively the rollers 59 of the corresponding levers 58. One complete rotation of the shaft 49 is accompanied by such a degree of longitudinal movement that but a single one of the cams mounted thereon is in service at any one time.

It will be understood that by continuing the rotation of the crank-arm 30 the operations may be caused to occur successively and the voltage gradually varied. If it is desired to lower the voltage, it is only necessary to reverse the direction of rotation of the operating-lever, and by virtue of the lost-motion connections between the gear-wheel 38 and the quill 42 and between the gear-wheel 70 and the shaft 66 each operation will occur at the proper instant.

Since the circuits through the various 40 transformer-windings remain closed regardless of the position occupied by the operating-handle of the regulator, it is evident that my invention is particularly useful in connection with circuits which it is absolutely prohibitive to open.

It will be also understood that the transformer-winding may be divided into any desired number of parts and that the regulator may be adapted for use with such transformers by employing a corresponding number of switches which may be operated in a similar manner, and I therefore do not intend to limit my invention to the precise number, structure, or arrangement of switches here 55 shown and described.

I claim as my invention—

1. The combination with means for successively operating a series of switches, of means for alternately operating two other 60 switches.

2. The combination with means for first closing one switch of a series and then opening the last preceding switch of that series, the operation of the switches continuing to 65 the end of the series, of means for next clos-

ing one of a pair of switches and then opening the other, the two switches being alternately opened and closed.

3. The combination with a quill, of a shaft actuated thereby having a threaded portion 70 at one end, a stationary nut with which said threaded portion engages, and cams mounted on said shaft.

4. The combination with an operating-handle and a pinion actuated thereby, of a 75 gear-wheel meshing with said pinion, a shaft to which said gear-wheel is rigidly secured, a quill loosely mounted on said shaft, and cams on said quill.

5. The combination with an operating-handle and a pinion actuated thereby, of a 80 gear-wheel meshing with said pinion, a shaft to which said gear-wheel is rigidly secured, a quill loosely mounted on said shaft, and a lost-motion connection between said shaft 85 and said quill.

6. The combination with an operating-handle and a pinion actuated thereby, of a gear-wheel meshing with said pinion, a shaft upon which said gear-wheel is rigidly secured, a quill loosely mounted on said shaft, cams on said quill, and a second quill actuated by 90 said shaft.

7. The combination with an operating-handle and a pinion actuated thereby, of a 95 gear-wheel meshing with said pinion, a shaft upon which said gear-wheel is rigidly secured, a quill loosely mounted on said shaft, cams on said quill, a second quill actuated by said shaft, and a shaft actuated by said second quill. 100

8. The combination with an operating-handle and a pinion actuated thereby, of a gear-wheel meshing with said pinion, a shaft upon which said gear-wheel is rigidly secured, a quill loosely mounted on said shaft, cams on said quill, a second quill actuated by 105 said shaft, a shaft actuated by said second quill and having a threaded portion at one end, and a stationary nut with which said threaded portion engages.

9. The combination with an operating-handle, a pinion actuated thereby and a gear-wheel meshing with said pinion, of a shaft to which said gear-wheel is rigidly secured, a 115 quill loosely mounted on said shaft, cams on said quill, a second quill actuated by said shaft, a shaft actuated by said second quill and having a threaded portion at one end, a stationary nut with which said threaded portion engages and cams mounted on said shaft.

10. The combination with a connecting-rod and a link, of a lever pivoted at one end to said link, a stationary bracket to which the other end of said lever is pivoted and toggle 125 members one of which is pivoted to said lever and the other of which is pivoted to said stationary bracket.

11. The combination with a connecting-rod and a link, of a lever connected at its free 130

- end to said link and fulcrumed at its other end and toggle members one of which is pivoted to said lever and the other of which is fulcrumed on a stationary axis.
- 5 12. The combination with a connecting-rod and a link, of a lever connected at its free end to said link and fulcrumed at its other end, toggle members one of which is pivoted to said lever and the other of which is fulcrumed on a stationary axis, and a lever fulcrumed on said axis to engage said second-named toggle member.
- 10 13. The combination with a switch-operating rod, a link connected to one end thereof and a rotatably-mounted cam, of a lever connected at its free end to said link and fulcrumed at its other end, toggle members one of which is pivoted to said lever and the other of which is fulcrumed on a stationary axis and provided with a roller to be engaged by said cam.
- 15 14. The combination with a switch-operating rod, a link connected to one end thereof and a rotatably-mounted cam, of a lever connected at its free end to said link and fulcrumed at its other end, toggle members one of which is pivoted to said lever and the other of which is fulcrumed on a stationary axis, and a lever fulcrumed on said axis to engage said second-named toggle member and provided with a roller to be engaged by said cam.
- 20 15. The combination with connecting-rods and links, of levers connected at corresponding ends to said links, a shaft on which the other ends are fulcrumed, pairs of toggle members interposed between the levers and actuating devices, and cams on said shaft adapted to cause said toggle members to buckle.
- 25 16. The combination with connecting-rods and links, of levers connected at one end to said links, a shaft on which the other ends are fulcrumed, pairs of toggle members, cams on said shaft adapted to cause said toggle members to buckle, and a gear-wheel loosely mounted on said shaft and having lost-motion connection therewith.
- 30 17. The combination with connecting-rods and links, of levers connected at one end to said links, a shaft on which the other ends are fulcrumed, pairs of toggle members, cams on said shaft adapted to cause said toggle members to buckle, dogs on said shaft, a gear-wheel loosely mounted thereon and lugs on said gear-wheel with which said dogs are adapted to engage.
- 35 18. The combination with rotatable cams, of levers adapted to engage at corresponding ends with said cams and toggle members having knuckle-joint connections with said levers.
- 40 19. The combination with a quill, of a shaft that is actuated thereby and has a threaded portion at one end, a stationary nut with
- which said threaded portion engages, cams mounted on said shaft and switches actuated by said cams.
- 45 20. The combination with an operating-handle and a pinion actuated thereby, of a gear-wheel meshing with said pinion, a shaft to which said gear-wheel is rigidly secured, a quill loosely mounted on said shaft, cams on said quill and switches actuated by said cams.
- 50 21. The combination with an operating-handle and a pinion actuated thereby, of a gear-wheel meshing with said pinion, a shaft upon which said gear-wheel is rigidly secured, a quill loosely mounted on said shaft, cams on said quill, switches actuated by said cams, switch-tripping devices and lost-motion connections between said quill and said tripping devices.
- 55 22. The combination with an operating-handle and a pinion actuated thereby, of a gear-wheel meshing with said pinion, a shaft upon which said gear-wheel is rigidly secured, a quill loosely mounted on said shaft, cams on said quill, switches actuated by said cams, a second quill actuated by said shaft, a second shaft provided with cams and actuated by said second quill, and switches actuated by said cams.
- 60 23. The combination with an operating-handle and a pinion actuated thereby, of a gear-wheel meshing with said pinion, a shaft upon which said gear-wheel is rigidly secured, a quill loosely mounted on said shaft, cams on said quill, switches actuated by said cams, a second quill actuated by said shaft, a shaft actuated by said second quill and having a threaded portion at one end, cams on said shaft, switches actuated by said cams, and a stationary nut with which said threaded portion engages.
- 65 24. The combination with an operating-handle, a pinion actuated thereby and a gear-wheel meshing with said pinion, of a shaft to which said gear-wheel is rigidly secured, a quill loosely mounted on said shaft, cams on said quill, switches actuated by said cams, a second quill actuated by said shaft, a shaft actuated by said second quill and having a threaded portion at one end, a stationary nut with which said threaded portion engages, cams mounted on said shaft, switches actuated by said cams, and tripping devices for said switches.
- 70 25. The combination with a switch-operating rod and a link, of a lever pivoted at one end to said link, a stationary bracket to which the other end of said lever is pivoted, toggle members one of which is pivoted to said lever and the other of which is pivoted to said stationary bracket, means for actuating said toggle members slowly in one direction, and means for tripping said members.
- 75 26. The combination with a switch-operating rod and a link, of a lever connected at its free end to said link and fulcrumed at its

other end, toggle members one of which is pivoted to said lever and the other of which is fulcrumed on a stationary axis, and means for operating said toggle members.

5 27. The combination with a switch-operating rod and a link, of a lever connected at its free end to said link and fulcrumed at its other end, toggle members one of which is pivoted to said lever and the other of which is fulcrumed on a stationary axis, a lever fulcrumed on said axis to engage said second-named toggle member, and means for actuating the second lever.

10 28. The combination with a series of switches and toggle-joint mechanisms for closing them, of a plurality of interconnected

shafts provided with operating-cams and a single handle for operating said shafts.

29. The combination with a series of switches and a plurality of interconnected 20 shafts and quills provided with cams, toggle-joint mechanisms actuated by said cams to close and open said switches in a predetermined order, and a single handle for operating said devices.

In testimony whereof I have hereunto subscribed my name this 8th day of April, 1904.

HARVE R. STUART.
